Primary Examiner — Holly Baynam*Assistant Examiner* — Rhea Shields(74) *Attorney, Agent, or Firm* — Harness, Dickey & Pierce, P.L.C.(57) **CLAIM**

The ornamental design for a reticle, as shown and described.

DESCRIPTION

FIG. 1 is a front view of a reticle in accordance with our new design;

FIG. 2 is an enlarged view thereof;

FIG. 3 is another enlarged view thereof;

FIG. 4 is an enlarged view of FIG. 3; and,

FIG. 5 is another enlarged view of FIG. 3.

In the drawings, the broken lines are for the purpose of illustrating environment only and form no part of the claimed design.

1 Claim, 3 Drawing Sheets(56)
